Elemir J. Ney, of Lowell, Mass
Assignor to
The Lowell Manufacturing Company,
Letters Patent No. 1619, dated Aug. 5, 1862,

The schedule referred to in these Letters Patent and making part of the same.

To all whom it may concern:

Be it known that I, Elemir J. Ney, of Lowell, in county of Middlesex and State of Massachusetts, have originated and designed a new Pattern for Carpets or other fabrics, of which the following is a full, clear and exact description, reference being had to the accompanying drawings, making part of this specification.

A. is an eight pointed figure surrounded by the frame

1, which is in turn surrounded by a band of small irregular balls, 2.

A broad band or ribbon 3. surrounds the figures before mentioned, and supports the groups of flowers 4, 4, 4, 4, from which, small leaves extend toward and around the band or balls 2. B and C, when matched form a figure composed of eight leaves surrounded by a band of sprigs resting on the dotted ground 5. This ground is enclosed by the frame 6, which is bordered with sprigs. D, is a set group of leaves and flowers. figs. 7 and 8, when matched form another set group of leaves and flowers. Scattered throughout the design are small branches with leaves and flowers attached, which rest on a ground work of small lines and crosses.

The remaining parts of the drawing are simply sections of figures similar to those before specified.

The colors employed for the different portions of the design may be varied to suit the taste and wish of the manufacturer.

Claim.

What I claim as my invention and desire to secure by Letters Patent, is the design or pattern for carpets or other fabrics herein set forth.
